CLAIM

The ornamental design for a suspension assembly, as shown and described.

DESCRIPTION

FIG. 1 is a perspective view showing the top, front, and right side of a suspension assembly having the inventive design; FIG. 2 is a front elevational view of the suspension assembly shown in FIG. 1;

FIG. 3 is a top view of the suspension assembly shown in FIG. 1;

FIG. 4 is a bottom view of the suspension assembly shown in FIG. 1;

FIG. 5 is a right elevational view of the suspension assembly shown in FIG. 1;

FIG. 6 is a left side elevational view of the suspension assembly shown in FIG. 1; and,

FIG. 7 is a back elevational view of the suspension assembly shown in FIG. 1.

The broken line showing of bolts and hardware in FIGS. 1-7, the upper recesses shown in FIGS. 1 and 3, attachment holes in FIGS. 1, 3, and 4, and portions of a mounting element shown in FIGS. 2 and 5-7 is for the purpose of illustrating environment and forms no part of the claimed design.
